United States Patent Office

Des. 191,811
Patented Nov. 21, 1961

191,811

DISPLAY STAND

Neville Levinson, 34 Coulson Ave., Toronto,
Ontario, Canada

Filed June 12, 1961, Ser. No. 65,552

Term of patent 14 years

(Cl. D80—9)

The sides of the display stand not shown are substantially the same in appearance as the sides shown.

I claim:

The ornamental design for a display stand, as shown and described.
